(57) **CLAIM**

The ornamental design for a body exerciser as shown and described.

DESCRIPTION

FIG. 1 is a perspective view of a body exerciser showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is an enlarged view of portion 9 shown in FIG. 1.

FIG. 10 is an enlarged view of portion 10 shown in FIG. 2.

FIG. 11 is an enlarged view of portion 11 shown in FIG. 3.

FIG. 12 is an enlarged view of portion 12 shown in FIG. 3.

FIG. 13 is an enlarged view of portion 13 shown in FIG. 4.

FIG. 14 is an enlarged view of portion 14 shown in FIG. 5; and,

FIG. 15 is an enlarged view of portion 15 shown in FIG. 7.

The dot-dash broken lines represent boundaries of the enlarged portions and form no part of the claimed design.

1 Claim, 15 Drawing Sheets
